DESIGN FOR A TOASTER CASING

Andrew S. Knapp, St. Louis, Mo., assignor to
Knapp-Monarch Company, St. Louis, Mo., a
corporation of Missouri

Application May 21, 1935, Serial No 56,947

Term of patent 3½ years

To all whom it may concern:

Be it known that I, Andrew S. Knapp, a citizen of the United States and a resident of the city of St. Louis and State of Missouri, have invented a new, original, and ornamental Design for a Toaster Casing, of which the following is a specification, reference being had to the accompanying drawing, forming part thereof.

Figure 1 is a perspective view of a toaster casing illustrating my new design.

Figure 2 is a front elevational view of the same. Figure 3 is an end elevational view thereof; and Figure 4 is an enlarged sectional view on the line 4—4 of Figure 2 showing a section through the door of the toaster casing.

I claim:

The ornamental design for a toaster casing substantially as shown and described.

ANDREW S. KNAPP.
